HEATING STOVE.

No. 20,418.

Patented Dec. 16, 1890.

UNITED STATES PATENT OFFICE.

JOHN K. McLAUGHLIN, OF PHILADELPHIA, ASSIGNOR TO THE BUCKWALTER STOVE COMPANY, OF ROYER'S FORD, PENNSYLVANIA.

DESIGN FOR A HEATING-STOVE.

SPECIFICATION forming part of Design No. 20,418, dated December 16, 1890.

Application filed November 24, 1890. Serial No. 372,559. Term of patent 3½ years.

To all whom it may concern:

Be it known that I, JOHN K. McLAUGHLIN, a citizen of the United States, residing in the city and county of Philadelphia, State of Pennsylvania, have invented and produced a new and original Design for Stoves, of which the following is a specification, reference being had to the accompanying photograph, forming part thereof.

10 The leading features of my design for a stove are as follows: an ornamental dome, an urn thereon, a wall below the dome having corner-pieces with heads thereon, sides with scroll-work and a scroll-door, sides with 15 open scroll-work and wings at the corners, ornamented foot-rests below the swells of the wings, and a scroll-work base with feet.

In the photograph, A designates a stove embodying the features of my design and consisting of the dome 1, the urn 2, the wall 3, 20 with corner-pieces 4 and heads 5, the sides with scroll-work 6, the open scroll-door 7, the sides with scroll-work 8 and wings 9, the rests 10, the scroll-work base 11, and feet 12.

I claim—

25 A design for a stove, as shown and described.

JOHN K. McLAUGHLIN.
